R. L. DEZENDORF

GUN

Original Filed June 30, 1920

Inventor

R. L. DEZENDORF.

By his Attorneys
Bartlett & Browne, Inc.

UNITED STATES PATENT OFFICE.

RICHARD LEE DEZENDORE, OF RICHMOND HILL, NEW YORK.

GUN.

Application filed June 30, 1920, Serial No. 392,911. Renewed September 22, 1923.

To all whom it may concern:

Be it known that I, RICHARD L. DEZENDORE, a citizen of the United States, residing at Richmond Hill, county of Queens, 5 and State of New York, have invented a certain new and useful Improvement in Guns, of which the following is a full, clear, and exact description.

My invention relates to improvements in 10 guns and has for its object to provide a gun which may be made of fairly light weight and which when being discharged is substantially noiseless and flashless. It is adapted for throwing projectiles and 15 particularly adapted for throwing grenades and the like a considerable distance without attracting attention.

The following is a description of an embodiment of my invention, reference being 20 had to the accompanying drawings, in which,

Fig. 1 shows a plan view of the gun, parts being in section so as to show the internal construction thereof;

Fig. 2 is a sectional view on the line 2—2, Fig. 1.

Referring more particularly to the drawings, 1 is an expansion chamber having an explosion chamber 2 projecting therein and 30 carried by a screw plug 3 adapted to receive a cartridge. The far end of the expansion chamber is closed by a plug 4. 5 is a barrel adapted to receive at its inner end 6 a projectile. The barrel 5 constitutes a 35 projectile chamber and extends into a catch chamber 7, having a screw-threaded connection 8 with the barrel 5. 9—9 are trunnions connected to the expansion chamber 1 and the barrel 5, by which the gun may be 40 supported if desired. The expansion chamber 1 is connected to the chamber 7 by pipes 11, 12 and 13, which pipes are also connected to a reservoir 14 closed by a removable screw cap 15. To aid in reducing 45 the noise when no liquid is used the perforated screen 11' may be used at the top of the pipe 11. The connections 11, 12 and 13 form a trap for oil or other liquid between the expansion chamber 1 and the 50 chamber 7. The bottom of this trap is also between the explosion chamber and the reservoir 14, which is connected to the trap beyond its connection with the chamber 7, so that pressure in the expansion chamber 55 tends to force liquid from the trap into the reservoir. The casing of the chamber 7 is

provided with an arm 16, to which is pivoted a movable link 17 carrying a breech-block 18 pivoted thereto at 19 and adapted to close the rear end of the chamber 60 7 after the projectile has been introduced into the barrel 5. The outer end of the arm 17 is provided with a ring 20, pivoted thereto and lying in a groove in a breech-block 21, which is adapted to be screwed upon the 65 end of the plug 3 closing the rear end of the explosion chamber 2, and acting to hold the breech-block 18 in position. This breech-block is provided with a firing pin 23, which is adapted to be actuated by a hammer 24, pivoted at 25 to an extension 26 from the breech-block 18.

In using this gun the reservoir 14 is partially filled with some liquid lubricant, such as oil, as indicated by the dotted line 75 therein. This lubricant forms a seal for the lower end of the pipe 12 leading to the chamber 7. A projectile is placed within the inner end 6 of the barrel and a cartridge is inserted in the plug 22, as shown. The 80 breech-block 21 is then screwed upon the plug 22 so as to be held in place and at the same time hold the breech-block 18 securely within the end of the chamber 7. The gun is then discharged by causing the hammer 85 24 to hit the firing pin 23.

As the gun is discharged the gases formed enter the expansion chamber 1 and exert a pressure therein which is transmitted 90 through pipes 11, 12 and 13, to the chamber 7 where the gases further expand and, acting upon the projectile within the barrel 5, expel the same. The pressure from the expansion chamber 1 while being communicated to the chamber 7 forces the oil which 95 is in the connection 13 partially back into the reservoir 14 and partially through the connection 12 into the chamber 7, where some of it is caught while some of it is discharged through the barrel 5 together 100 with the projectile. After the pressure has been relieved oil returns from the reservoir 14 so as to seal the lower end of the connection 12, whereupon the gun may be reloaded and discharged again, the operation being 105 repeated until the oil in the reservoir 14 is used up.

The explosive charge used is preferably slow burning cellulose which, upon discharge, is substantially consumed, it being 110 held in the far end of the expansion chamber until consumption takes place, the open-

ing from that chamber being in such position as not to afford a ready exit for unconsumed explosive. In this way the full power of the explosive charge is made use of. While the gases push aside most of the lubricant, forcing it to return to the reservoir, some of the lubricant follows the projectile and acts as a hydraulic cushion or packing, and also to lubricate the barrel.

10 As the lubricant returns from the reservoir it interferes with the movement of the gases so as to make the gun practically noiseless. Since substantially complete consumption of the charge takes place in the expansion 15 chamber, the gun is substantially flashless even when oil is not present in the reservoir or trap.

I prefer to connect the trap with the expansion chamber at a point to the rear of the 20 discharge opening of the explosion or cartridge chamber, but this is not necessary if the gun is otherwise constructed so as to secure complete combustion of the explosive. The trap between the explosion chamber 25 and the projectile chamber 6 is however necessary to secure the desired results.

As will be evident to those skilled in the art my invention permits of various modifications without departing from the spirit 30 thereof or the scope of the appended claims.

What I claim is:

1. In a gun, the combination of an explosion chamber having a breech-block and a firing pin, a projectile chamber, a connection 35 between said chambers such that gases can pass from said explosion chamber to said projectile chamber, a trap for liquid in said connection such that liquid therein normally separates said two chambers and 40 means for supplying liquid to said trap independently of said chambers.

2. In a gun, the combination of an ex-

plosion chamber having a breech-block and a firing pin, a projectile chamber, a connection between said chambers such that 45 gases can pass from said explosion chamber to said projectile chamber, a trap for liquid in said connection such that liquid therein normally separates said two chambers, an expansion chamber having its front end connected to said explosion chamber and its rear end connected to said trap, and means for supplying liquid to said trap independently of said chambers.

3. In a gun, the combination of an explosion chamber having a breech-block and a firing pin, a projectile chamber, a reservoir, a trap connected to said reservoir and located between said explosion chamber and projectile chamber so that liquid therein 50 normally interrupts the connection between said two chambers, and a chamber surrounding said projectile chamber and located between it and said trap.

4. In a gun, the combination of an explosion chamber having a breech-block and a firing pin, a projectile chamber, a reservoir, a trap between said explosion chamber and projectile chamber connected to said reservoir so that liquid therein normally 55 interrupts the connection between said two chambers, breech-blocks for each of said chambers and common means for securing both of said breech-blocks.

5. In a gun, the combination of an explosion chamber, an expansion chamber connected thereto, a projectile chamber, a trap connecting said projectile chamber with said expansion chamber, a reservoir connected to said trap beyond its connection with said 70 projectile chamber, and breech-blocks for said chambers.

RICHARD LEE DEZENDORF.
